UNITED STATES PATENT OFFICE.

EDWARD J. CRESSEY, OF WICHITA, KANSAS.

AUTOMATIC TELEPHONE AND RESPONDING APPARATUS.

1,192,993.

Specification of Letters Patent.

Patented Aug. 1, 1916.

Application filed March 11, 1915. Serial No. 13,746.

To all whom it may concern:

Be it known that I, EDWARD J. CRESSEY, a citizen of the United States, and a resident of Wichita, in the county of Sedgwick and 5 State of Kansas, have invented certain new and useful Improvements in Automatic Telephone and Responding Apparatus, of which the following is a description, reference being had to the accompanying drawings, forming a part of this specification.

The invention relates particularly to a method for producing automatically telephonic responses of predetermined acoustic records. Second. To transmit such response 15 instantly to the party calling and repeating such response to prevent misunderstanding by such party. Third. To transmit a response to the party calling that will inform such party of the presence of the subscriber, said response being continued at intervals during a certain period of time. Fourth. Means for cutting out the phonographic mechanism, electrically operated, whereby the telephone proper only is in action. Fifth. To automatically control the 20 position of the record reproducing mechanism. Sixth. To govern the movements of the record reproducing mechanism and produce a plurality of like responses. Seventh. 25 To record the calls transmitted phonographically to the reproducing instrument. Eighth. Electrically operated means whereby the automatic telephonic responding apparatus can be set to repeat any desired 30 code answer, said means being adapted to be operated locally or from a distance. Ninth. Electrically operated means for opening the telephonic talking circuit, when the receiver is off the hook, thereby enabling 35 a call to be made.

The invention embodies certain improvements over my invention filed October 14, 1913, Serial No. 795,099.

The responding apparatus is the combination of a phonograph and a telephone, together with other mechanisms, and is an instrument adapted to be furnished to a subscriber in addition to his regular telephone set. It enables a subscriber to leave any 45 message, which will be transmitted to a party calling over the talking circuit of the telephone. Its uses are practically unlimited, being of particular value to doctors, lawyers, real estate and business men generally, both for office and residence uses.

On the records of the apparatus are num-

bers, each of which represents a code for some special message which is fully explained in the code directory, similar to or made a part of the regular telephone directory. There is practically no limit to the number of code numbers, or messages that can be transmitted by the responding apparatus. To illustrate, let "Respondo No. 1." be the code number for the message "Will be back at two o'clock." If any party, calling for instance a doctor's office during his absence, the doctor's apparatus being set at No. 1, will immediately answer such call twice with the code message "Respondo No. 1." "Respondo No. 1," the object of repeating the code number is to avoid misunderstanding the response. The party calling then refers to the code directory and finds the doctor "Will be back at two o'clock." "Respondo No. 8" may be the code number for "At home" in which case party could reach the doctor by calling his residence number indicated in the regular telephone directory. Suppose now the doctor gets a call to go to the Wichita hospital at two o'clock and finds he will not have time to go to his office to reset his machine, he can call the information operator at central and instruct her to change his office apparatus to the code desired, for instance let "Respondo No. 28" refer to "Call Wichita hospital." Central having a reset machine through which she can set any responding apparatus to any number desired, makes the change from No. 1 to No. 28 on the doctor's office machine. These and other features enable the subscriber's friends or business associates to quickly get into communication with the subscriber, whether at the theater, church, hotel or other place having telephonic communication.

Another valuable feature of the apparatus in this; when you are around the office or home, perhaps in the yard, the telephone often rings and before you can reach it, the party calling has gone. The apparatus can be set at "Hold the line, your party will be here in a minute" which by certain mechanism on the apparatus will advise the party calling that you are coming.

All the above mentioned results are obtained and fully explained in the following description, reference being had to the accompanying drawings, in which similar numerals of reference indicate corresponding parts in all the figures of the drawings.

In the drawings, Figure 1 is a front elevation of the automatic telephone and responding apparatus. The indicator dial plate is removed, its position being indicated by the dotted circle. Fig. 2 is a front view of the indicator plate, showing nearest the edge, numbers for the predetermined answers or code responses, the numbers nearest the center of the dial indicating the number of responses or calls received. The hands shown point to these numbers. Fig. 3 is a rear view of Fig. 2. Fig. 4 shows a right hand end view of the apparatus seen in Fig. 1. Fig. 5 is a rear view of the apparatus, omitting certain mechanisms seen in Fig. 1, and showing principally the electromagnets, motor relays, binding posts for the wiring system and the cut outs for ringing and talking. Fig. 6 shows the insulated disk, also seen in Fig. 5, for breaking the ringing circuit. Fig. 7 is a side view of the electromagnets for opening and closing the telephone transmitter circuit. Fig. 8 is a side view of a switch inside a desk telephone. Fig. 8^A is a side view of a modification of such switch. Fig. 8^B is a front view of the switches seen in Figs. 8 and 8^A. The switch seen in Fig. 8 only is used in this specification, controlling both the regular telephone and the responding apparatus instruments. Under certain conditions of wiring this switch is used for the apparatus only, and the extra switch seen in Fig. 8^A is employed for the regular telephone, both switches, however, being operated by the telephone hook lever. Fig. 9 is a plan view of the mechanism suspended from the top plate of the apparatus, being an inverted view, showing the push button release, release magnet and shaft and mechanism for closing talking circuit of the apparatus indicating each call. Fig. 10 is a sectional rear view of the ratchet bar and guide for carrying the arm of the diaphragm holder. Fig. 11 is a view showing the step by step magnets, ratchet bar and dog, also switch on talking circuit of the apparatus. Fig. 12 is a front view of the ratchet and dog mechanism seen in Fig. 1 for recording calls. Fig. 13 is a sectional front view of the governor brake mechanism shown in Fig. 1. Fig. 14 is a sectional view taken through the diaphragm holder, record, cam, showing the driving mechanism and the bar for closing the "Hold the line" clutch mechanism. Fig. 15 is a plan view showing the bar for closing the "Hold the line" clutch mechanism, also the spring for returning the diaphragm holder after the response is made. Fig. 16 is a sectional view taken along the line X—X in Fig. 1, looking in the direction of the arrows, and shows the end gearing, drive gear with belt connecting the cylinder pulley, parts being broken away to show portions of the housing. Fig. 17 is a plan view of a portion of the record

cylinder gears connecting the threaded shaft which carries the diaphragm holder, gears connecting the cam, and showing the "Hold the line" contact disk, back gears, electromagnet and contact drum sections. Fig. 17^A is a sectional view of the armature controlling the small clutch pin gear seen in Fig. 17. Figs. 18, 19 and 20 are end views of the three sections of the contact drum. Fig. 21 is a vertical sectional view taken along the shaft through the contact drum sections and showing the return spring. Fig. 22 is a sectional view taken along the line Z—Z in Fig. 1 looking in the direction of the arrows, and showing the back gears for the "Hold the line" response, clutch pin and electromagnet. Fig. 23 is a sectional view of the cam shaft taken along the line X—X in Fig. 17 and also showing the lever for raising and lowering the diaphragm holder and allied parts. Fig. 23^A is a sectional view of the cam shaft taken along the line Z—Z in Fig. 17 and also showing the lever for raising and lowering the diaphragm holder and allied parts. Fig. 24 is a top view of the dial plate on the reset machine. Fig. 25 is an edge view of such dial plate. Fig. 26 is a top view of the reset machine, with the dial plate removed, the position of the dial plate being indicated by the dotted circle. Fig. 27 shows a side of the reset box removed to expose the reset mechanism to view. Fig. 27^A is an elevation of that portion of the mechanism seen in Fig. 27 controlling the setting of the dial plate. Figs. 28, 29 and 30 are plan views of the three ratchet wheels seen in the reset box in Fig. 27. Fig. 31 is a top view of reset contact gear. Fig. 32 is an edge view of reset contact gear. Fig. 33 is a top sectional view of reset contact showing make and break. Fig. 34 is a side view of switch in reset box. Fig. 35 is a plan view showing the wiring diagram.

Referring to the drawings, in Figs. 1 and 4 is seen a framework for the phonographic apparatus comprising a bed plate 36, having legs 37, cross braces 38 and a top plate 39. In a standard 40 attached to the bed 39 is located the shaft 41 on which is mounted a cylinder 42 and on the cylinder 42 is a phonographic record 43 on which are recorded the code wordings in proper series and arrangement. At 44 is an electric motor, at 45 a motor shaft mounted in hangers 46 attached to the plate 39. The cylinder drum 42 is driven by the motor 44 through the shaft 45, belt 47 and pulley wheel 48. Housed in the standards 40 and 49 is a shaft 50 parallel to 45. The diaphragm holder 51 is mounted and slides on this shaft 50. At 52 is seen a telephonic transmitter wired at 52^A to the telephone circuit. 53 is the reproducing pin. At 54 is the indicator shaft at right angles to the shaft 50. In

Fig. 2 is seen the front face of the indicator dial 55. Fig. 3 shows a rear view of 55. In Fig. 1 the indicator dial 55 has been removed from the shaft 54 to uncover concealed mechanism, its position being indicated by the dotted circular line. The clips 56 on the rear of the indicator plate or dial 55 are useful for attaching the said dial to the top plate 39. Near the edge of the dial 55 are seen numbers in sequence from 0 to 31, these numbers as will be further explained have reference to certain code responses recorded in sequence on the record 43. The dial hand 57 attached to the shaft 54 stands at 0 normally. At the other end of shaft 54, see Figs. 5 and 6, is an insulated disk 58 having a flat place 59 on its periphery. When the indicator hand 57 stands at 0 on the dial 55, this flat place 59 stands directly over the shaft as in Fig. 6 for the purpose further explained. On the shaft 54 as seen in Figs. 9 and 10 is the ratchet wheel 60. Moving the hand 57 to any number such as 28 on the dial as seen at 57^x, revolves this shaft 54, whereby the ratchet wheel 60 engaging with a rack bar 61 on top of plate 39, through a slot 62 in such plate 39, will move the bar 61 and its attached guide holder 63. This holder slides on a shaft 64, parallel to 45, which is housed in the standards 40 and 65. The holder 63 is notched out from 66 to 67. The arm 68 attached to the diaphragm holder 51 is mounted and slides on the shaft 64 within the space 66-67 of the holder 63, being normally held at 66 by the spring 69.

The phonographic record 43 is properly prepared having a list of suitable code responses recorded thereon in sequence, such responses being numbered and recorded in a code or telephone directory available to all telephone uses. Presuming the subscriber to be a doctor and that he is called to the Wichita hospital, and that he has no one in his office to answer telephonic calls, by means of my invention any patients or parties calling him will be told to "Call the Wichita hospital." Supposing the code directory gave "Respondo No. 28" as the code response for "Call the Wichita hospital," then if the hand 57 were moved from 0 to 28 on the dial 55 as seen at 57^x Fig. 2, the arm 68 would be forced to travel carrying the holder 51 and pin 53 to the starting position on record 43 corresponding to such No. 28 on the dial. When the motor circuit is closed and the motor operates, the record 43 revolves and the reproducing pin is then put in contact with said record 43 by cam action as will be later described. The transmitter 52 then repeats the code words "Respondo No. 28" which answer is carried over the talking circuit of the telephone to the party calling, the transmitter being in circuit as

seen in Fig. 35. This party then refers to the code, then telephones the Wichita hospital and thereby reaches the doctor.

During the operation the guide 63 of course stands stationary, a dog operating 70 to prevent movement of the shaft 54 as will be later seen; the arm 68 however is carried toward the dotted position seen in Figs. 10 and 15. At 70 on shaft 41 is a small gear, at 71 is a stud pin housed in 40 on which 75 revolves a gear wheel 72 in mesh with 70 and another gear wheel 74 on a shaft 73, said shaft being parallel to 45 and being housed in the standards 40 and 49. Keyed to 73 is the small gear 75 driving the big 80 gear 76, supported by a stud pin 77 in a housing 78. The small gear 79 is attached to and revolves with 76, meshing with the gear 80 to a drive shaft 81 housed in the standard 82. On this shaft 81 is the cam 85 shaft 83 which revolves in the direction of the arrow Fig. 23.

Fig. 14 shows three levers 84, 85, 86 attached to the arm 68 and holder 51. The lever 84 is operated by the cam shaft 83 being held in contact thereto by the spring 87. The lever 85 has a tension spring 88 which tends to hold the threaded foot 89 in contact with a revolving threaded screw fashioned on the shaft 73 between the points 90 and 91, whereby the arm 68 and pin 53 will be forced to travel upon the record 43 at the proper time to produce phonographic responses. The lever 86 controls the up and down movement of the reproducing pin 53. The cam, acting upon the lever 84 controls the action of the levers 85 and 86. When the cam 83 and lever 84 stand as seen in Fig. 14, the portion 84^x of the lever 84 bears against the portion 86^x on lever 86 hinged at 92 whereby the upper portion of lever 86 holding the pin 53 is raised off of the record 43. The portion 84^x of 84 bears against the lever 85 hinged at 93, lifting the threaded foot 89 from engagement with the threaded screw on the shaft 73. When the cam 83 revolves farther and the lever 84 drops into the recess 94 on the cam, lever 84 does not act on levers 85 and 86 and the spring 95^x pulls the lever 86 down so that the pin 53 travels upon the cylinder record 43 since the spring 88 has drawn the foot 89 into engagement with the revolving threaded screw on 73, and the arm 68 is traveling toward the dotted position 67 as in Fig. 15. When the cam raises the lever 84, and the driving mechanism 73, 89 is thus disengaged and the pin 53 raised, then the spring 69 returns the arm 68 to its original position against 66.

Cam 83 in Figs. 14 and 23 is shown having two recesses 94, or more recesses might be added if desired. The object of a plurality of recesses 94 is to give a plurality of responses through the transmitter 52, as for instance, the mechanism will repeat the code 130

response "Respondo No. 28" twice since by action of the two recesses 94 and 94 and allied parts and the action of springs 69 on the arm 68, the pin 53 has been made to travel twice over the record corresponding to No. 28 on the dial to which the hand 57 is pointing.

It will be understood that the number of code numbers 0 to 31 inclusive might be varied or increased, each number as repeated by the apparatus having a separate meaning as explained by the code directory. For instance one response might be for special information, thus setting the hand to No. 30 15 on the dial would give the response "Respondo No. 30", the code directory would show this response to mean "Call responde information operator at central" upon calling her, any desired information left with 20 her by the subscriber would be given to the party calling.

Suppose the subscriber desires to cut out the apparatus from the telephone circuit, the hand 57 is set at 0 on the indicator dial 25 55 by means further explained. In this position the telephone proper only is in operation. The numbers 1 to 30 referring to code words, are adapted to furnish the person calling with desired information relative to 30 the whereabouts of the absent subscriber. Assuming the subscriber on the premises, if the hand 57 points to 0 he would answer the regular telephone call, the apparatus being 35 dead, but perchance he is at a slight distance but within hearing and desires to finish some work engaged upon before answering the telephone ring. In this event he has set the hand 57 to No. 31 on the dial 55, this moves the lever 84 to 95 on the cam shaft 83 where 40 only one recess 94 is seen as in Fig. 23A. The apparatus set to this position will answer "Hold the line, your party will be here in a minute" or similar recorded information, said response being repeated once 45 at every revolution of the cam shaft 95 for a certain period, say for ten or twelve revolutions occupying an elapsed time of say three minutes. The cam shaft 83 revolves only once for the code responses such as "Respondo No. 28" previously referred to, the 50 operation of the cam shaft in either case being controlled by certain means herein-after set forth.

Referring to the wiring diagram, Fig. 35, 55 the call comes in from central or "C" through the ringing circuit, the circuit is carried through section 96 of the contact drum by the wires 97, 97. At 98 is shown an electromagnet closing the motor circuit. 60 At 99 is shown a condenser. Disk 58 is shown revolved in Fig. 5, for instance to No. 28 as indicated by the hand 57 on the dial at 57°, the circuit closer at 100 being thereby lifted to make a contact and the 65 circuit closed. Fig. 6 shows the circuit

broken at 100° the spring portion 101 of the circuit closer resting on the flat portion 59 of disk 58, this being the position when hand 57 points to 0 on the dial 55 and the apparatus is dead.

When the circuit is closed and motor 44 is in operation, the speed of the revolving parts is controlled by the fly wheel, 102, governor 103, brake 104 and brake disk 105, Figs. 1 and 13. The brake 104 is attached to and suspended from a shaft 106 by the bar 107. The revolving governor 103 draws the brake disk 105 against the brake 104 causing movement of the bar 107 and shaft 106, said shaft being housed in the holder 80 108 suspended from the plate 39. This movement of shaft 106 performs two offices. First. As seen in Figs. 1 and 12, a bar 109 attached to the end of the shaft 106, has a ratchet 110 engaging a ratchet wheel 111 in rear of the indicator dial, said wheel 111 being loose on the shaft 54. Movement of the shaft 106 moves the wheel one notch by means of the ratchet 110. 112 shows a stop pawl. The hand 113 which is attached to the wheel 111 is seen pointing to No. 12 on the inner line of numbers. These numbers register the number of calls made during absence of the subscriber, since movement of the hand 113 has followed at each 90 call. Second. Fig. 5 shows the other end of shaft 106. 114 is an insulated bar attached to said shaft 106. The movement of shaft 106 occasioned by the movement of the bar 107 above referred to, throws 114 100 downwardly, acting on the parts forming the circuit closer 115 to close the talking circuit of the apparatus during the operation of the motor, and the phonograph mechanism answers "Respondo No. 28" 105 through the transmitter 43, which answer is carried to the party calling, over the regular telephone circuit. When the motor stops, the contact is broken at 115 and the talking circuit of the apparatus is cut out. 110

The motor is tripped as follows. Referring to Figs. 1, 15 and 17. At 116 is seen an insulated disk slidable on a key way on the cam shaft axle 81. This disk 116 rotates with the axle 81 but its position on the key-way can be changed for purposes later defined.

Supported in the standards 117, 118 on plate 39 is a shaft 119 and on this shaft is seen a spring 120 bearing against the standard 118. A base block 121 is slidably mounted on the shaft 119, the spring 120 normally holding the block 121 away from the standard 118. This block supports the wires 122, 122 of the motor tripping circuit, also the wires 123, 123 which assist in moving the disk 116 on its key way as later described. The ends of the wires 122, 122, 123, 123 travel in grooves 124, 124 formed in the periphery of the disk 116. 120 125 130

At 125, 125 in the grooves 124, 124 is a contact.

Referring to Figs. 1, 4, 17, 18, 19, 20 and 21 is seen a contact drum comprising three sections 96, 126, 127 sleeved on a shaft 128 supported by the standards 117, 118. This shaft sleeves into and supports the right hand end of the cam shaft axle 81 at 129. At 130 is seen an electromagnet. At 131, 132 are back gear wheels rigidly attached to a sleeve floating on axle shaft 73, these gears mesh respectively with the gears 134, 135 on shaft 128. The gear 135 is connected by the sleeve 136 to the drum sections 96, 126, 127 so that 135 revolving carries with it said drum sections. At 137 is a spring attached to the standard 117 and drum section 127. This spring normally holds the drum sections in the position seen in Fig. 17 where 20 a stop pin 138 on the flange of the gear wheel 135 is shown in contact with the stop post 139. At 140 is seen a circular armature for the magnet 130. The gear wheel 134 is provided with a shoulder 134^x the armature 140 as seen in Fig. 17^a being mounted between the gear 134 and its shoulder 134^x, movement of the armature toward 130 will therefore pull the gear 134 a slight distance to the right. The armature does not 30 revolve with the gear wheel 134. The gear wheel 134 and disk 116 are each provided with clutch pins as at 141 and 142 for the purpose further defined. At 143, Fig. 15, is seen a spring on shaft 128 bearing against the standard 118 and holding the armature 140 and attached gear wheel 134 away from the magnet 130 to a desired position with respect to the disk 116 for the purpose further explained.

Section 127 of the drum as seen in Figs. 17 and 18 comprises a metallic contact disk grooved at 144 and having an insulated point in said grooves at 145. Section 126 of the drum comprises an insulated disk grooved at 146 and having two contact points 147, 148 in the grooves 148^x. Section 96 of the drum comprises a metallic contact disk grooved at 149 and having an insulated point in said grooves at 150. The drum sections stand stationary as in Fig. 17 at all times except when the "Hold the line" response is made by the apparatus. The ends of the terminal wires 97, 97 are seen supported by a base block 151 and rest in contact in the grooves 149 of disk 96. The ends of the terminal wires 122^x, 122^x supported by the base block 151 rest on the contact point 147 on disk 126. The ends of the terminal wires 152, 152 supported by the block 151 rest on the insulated point 145 on disk 127.

When the motor circuit is closed, the disk 116 revolves and when the contact point 125 passes under the wires 122, 122 the trip circuit is closed through wires 122^x 122^x in con-

tact at 147 on the drum section 126, thereby energizing the magnet 153, thus releasing the latch 154 and breaking the contact at 155 whereby the motor circuit is cut out. However the momentum of the flywheel 70 102 and revolving parts carries the contact point 125 past the point of contact with the wires 122, 122 and the trip circuit is open again.

In Figs. 14 and 15 is seen a bar 156 attached to the guide 63, this bar 156 terminates in a block 157 having a recess 158 into which the shaft 119 may enter. When the hand 57 is set at No. 31 on dial 55, this being the "Hold the line" number, the block 157 80 moves to the right as in Fig. 15, pushing the base block 121 against the spring 120. The terminal wires 122 and carrying wires 123 attached to said block 121 and resting in the grooves 124 in the slidable disk 116, 85 carry said disk toward the gear wheel 134. The spring 143 holding the gear wheel 134 toward the disk 116, the clutch pins 141 and 142 will engage on rotation of the shaft 81 whereby the back gear wheels 134, 131, 90 132, 135 will revolve, thus slowly revolving the drum sections 96, 126, 127 against the spring tension 137.

As previously described the wires 122^x, 122^x are on contact normally at 147 so that 95 the motor trip circuit is closed when the wires 122, 122 come on contact at 125 on the revolution of the disk 116. In the "Hold the line" response, however, the contact is broken at 147 since the drum is revolving 100 and the motor trip circuit is not closed until a new contact 148, on the drum section 126, for the wires 122^x, 122^x coincides with the contact of wires 122, 122 at 125, 125 on disk 116. The back gear wheels 134, 131, 132, 105 135 are geared so that the disk 116 makes a plurality of revolutions before such contacts 148 and 125 coincide as above. For instance the timing may be so arranged that the motor tripping circuit will not close for 110 several minutes. During all this time, therefore, the cam shaft 83 has been acting on 84 at 95 and the phonographic apparatus has been repeating the words "Hold the line, your party will be here in a minute" 115 at each revolution of the cam shaft 83. Should the subscriber neglect answering the call, the apparatus would go dead after the motor circuit was tripped and another telephone ring or call would not close the motor 120 circuit because an insulated point 150 on disk 96 is in contact with the wires 97, 97 of the ringing circuit, whereby the circuit is broken through the apparatus, said point 150 being in line with 148. When however 125 the subscriber answers the ring, either when the time limit has expired and the apparatus has gone dead or during the time the apparatus is repelling "Hold the line, etc.," the removal of the receiver from the hook 130

lever 159 will make the contact 160, Fig. 8 thus energizing the magnet 130, since the circuit is closed, the wires 152, 152 being in contact on the disk 127, the armature 140 therefore drags the clutch pin 141 on gear 134 from engagement with the clutch pin 142 on the disk 116, then the spring 137 returns the drum sections back to normal as in Fig. 17.

When the receiver is left off the hook, the telephone transmitter circuit is closed, the ringing circuit is closed all the time but the bell will not ring while the telephone transmitter circuit is closed. Under ordinary conditions, central would cut off the telephonic service to a subscriber whose receiver was off the hook, after a period had elapsed, or else send some one to hang up the receiver. One of the main objects of my invention is to enable the said subscriber's transmitter circuit to be broken by central under such conditions, thus enabling a ring to come in. At 161 is seen a relay magnet, at 162 and 163 are electromagnets. By pressing a button 164 at central as will be later described, the magnet 161 is energized by a battery at central or by a special battery through line 1, or 165 and ground 166, this closes the circuit energizing the magnets 162 and 163. The magnet 162 being energized, the contact 167 in the transmitter circuit is broken and contact 168 closed as in Fig. 7 thus enabling central to ring the subscriber who notices his receiver is off the hook and he hangs it up, thus closing contact at 169 Fig. 8 thus energizing the magnet 170 which raises the hook 171 hinged to the armature 172, the weighted bar 173 then breaks the contact 168 and makes the contact at 167 closing the transmitter talking circuit again.

The hand 57 can be set at 0 on the indicator dial 55 by two means, a push button 174, or a push button 164 on a reset machine Fig. 27. The reset machine is preferably located at central.

In Figs. 1, 4, 9, 35 is the push button 174 on a shaft 175 supported by standards 176, 177 suspended from the plate 39. A spring 178 shouldering against a pin 179 on the shaft 175 breaks the contact at 180. Pushing the button 174 closes the circuit at 180 energizing the magnet 163. The armature of 163 is attached to a dog 181 which passes through a hole in a ratchet bar 182. At 183 is seen a tension spring. When the circuit is closed through the magnets 163, the armature releases the dog 181 from engagement with the ratchet wheel 184. Also a pin 185 in the end of the dog 181 pulls the ratchet bar 182 from engagement with the wheel 184. Then the spring 186 returns the hand 57 to 0 on the dial 55, also the disk 58 to the position seen in Fig. 6 and the diaphragm holder 51 and allied parts to their

proper position corresponding to 0 on the dial. It will be observed that this operation will remove the pressure of the block 157 from the base plate 121 as in Fig. 15, the spring 120 would move the disk 116 away from the gear wheel 134 breaking the clutch action of pins 141, 142 whereby the spring 137 would return the drum sections back to normal as in Fig. 17, providing they had moved.

As previously described, the relay magnet 161 was energized by pressing the button 164 at central thus closing the circuit and energizing the magnets 163, the action of the armature and dog 181 of the magnets 163 is thus the same whether button 174 or button 164 be pushed, and the hand 57 will always return to 0.

Referring to Figs. 24 to 35 inclusive. At 187 is seen a box containing the reset apparatus. 188 represents the reset dial on a main shaft 189 in bearings 190, 191 on portions of the box frame. 192 represents numbers and holes on the dial 188, 193 is a reset stop, 194 is a stop on the dial. 195 and 196 are ratchet wheels on the shaft 189. 197 is a contact gear on shaft 189 and at 198 is an insulation on such gear. On a standard 199 supported by the plate 200 in the box is seen a contact 201 attached to the negative line or 202 on an insulated block 203. This contact 201 is normally not in contact with the teeth of the contact gear 197 but stands between the teeth as in Fig. 33, the insulated disk 198 preventing the point 201 from dropping down between the teeth and forming a contact. Contact is made when the shaft 189 and gear contact 197 revolve by clock mechanism, the teeth on the gear touching the point 201 in sequence. At 165 Fig. 34 is seen the positive line, ground line 204 and negative line 202. Pushing the button 164 as previously mentioned makes a contact 165—204 which performs the function of energizing the magnets 161, 162, 163 for the purposes before explained. At 205 is a ratchet wheel attached to a clock escapement 206. A spring 207 is attached to the shaft 189. At 208 is shown a ratchet on a disk 209 attached to the shaft 189, this ratchet 208 engages with the wheel 205.

At 164 is seen the push button, previously mentioned, attached to the shaft 210 housed in the frame 199. On the shaft 210 is a base block 211 supporting a spring 212 which acts against a beveled cam block 213 keyed on the shaft 210. A bar 214 is attached to the spring plate 215. At 216 is a pawl bar housed in the hanger 217 and frame 199. On 216 at 218 is a shoulder, bearing against this shoulder 218 is a spring 219, the bar 216 is threaded through a hole in the spring bar 215 and the spring 219 presses against 215; on the opposite side of the spring 215 and on the bar 216 is a shoulder 220. The spring 215

normally holds the bar 216 from engagement with the ratchet wheel 196. At 221 is a beveled cam block on the shaft 210. At 222 is a pawl bar housed in 217 and 199. On 222 is a pin 223. At 224 a spring attached to 199 normally holding the bar 222 in engagement with the ratchet wheel 195. The reset dial 188 cannot be advanced to any number when the bars 216, 222 stand as in Fig. 27^A, their 10 normal position. Pushing on the button 164, the hand 57 has returned to 0 on 55, now the cam 221 acts on the pin 223 forcing disengagement of the bar 222 from the ratchet wheel 195, also the cam 213 acts on the bar

15 214 on the spring 215 so that 215 pushes the spring 219 against the shoulder 218, whereby the bar 216 is forced into engagement with the ratchet wheel 196. This action reverses the position of such pawl bars with 20 reference to the ratchet wheels 195, 196. Now the dial 188 can be set to a number such as 28.

The central operator places a stylus in the hole 28 in the set of numbers 192 on the dial 188 and by this means rotates the dial 188 in 25 the direction of the arrow until the stylus in hole 28 comes to the stop 193. The stylus is removed and the push button 164 then released, the dial 188 is now returned to the 0 position as in Fig. 24 by means of the clock 30 escapement. The contact point 201 on line 202 is now being touched in sequence by the teeth on the contact gear 197. At each contact therefore the circuit through line 202 and ground is closed and opened. This circuit leads to a relay magnet 225 and ground 35 166 closing the circuit and energizing magnets 226, controlling the step by step mechanism; the ratchet bar 182 is attached to the armature 227 of 226, at 228 is seen the spring 40 for the armature. At each contact therefore of 201 and a tooth on the gear contact 197, the armature 227 and attached ratchet bar 182 controlled by spring 229 will move and thus revolve the gear wheel 184 one notch, 45 this gear being attached to the shaft 54 will therefore move this shaft and its attached mechanism, namely the hand 57 and the diaphragm holder 51 and allied parts, the final position of the hand 57 pointing to the number 28 on the dial 55 and the reproducing pin 53 is thus brought to the proper position 50 over the record 43 to repeat the code response "Respondo No. 28" should a ring come in. Pressing the button 174 brings the hand 57 to 0 as previously described, the subscriber is thus enabled to push the hand 57 to No. 28 on the dial and the pin 53 to the 55 position mentioned above.

The following briefly summarizes the action and advantages of the apparatus and allied parts. During the absence of the subscriber, the apparatus is set to any number of a predetermined code or program and then if a ring comes in, the regular telephone bell rings and a relay on the apparatus closes a

motor circuit. This relay is held closed by a latch. This motor operating, revolves the phonograph cylinder of a standard phonograph, it also closes the talking circuit of the transmitter. The apparatus then repeats 70 the code answer twice, the cam that raises and lowers the reproducer has now made a complete revolution and the contact disk that revolves with the cam now passes under contact points, closing the circuit 75 through a magnet to raise the latch of the motor circuit relay, causing the motor to stop and the talking circuit of the apparatus to open.

When the apparatus is set on "Hold the 80 line" and a ring comes in, the operation is the same for any code answer except that the cam is now permitted to revolve ten or twelve times by means of a back gear which revolves a second set of contact disks; one of 85 these disks is in series with the contact disk that revolves with the cam and the two revolve together for about three minutes when the contacts on these disks coincide, closing the circuit of the magnet to raise 90 the latch of the motor circuit relay, causing the motor to stop and the talking circuit to open; if the apparatus completes its cycle before the subscriber answers, it goes dead and does not respond to another ring until 95 the subscriber either takes the receiver off the hook, thus closing a circuit through the magnet to release the back gear, or sets the apparatus to a new code number which act disengages the two clutch pins that drive 100 the back gear from the cam shaft. However, should the subscriber answer the call before the apparatus completes its cycle, when he takes the receiver off the hook, a circuit is closed through a magnet on the apparatus which releases the back gear, which allows the drum sections to return to normal, this cutting out of the circuit for energizing 105 magnet to release the back gear takes but a second and even now with the receiver 110 off the hook, no energy is used, and the contact disk continues to revolve until it closes the circuit through the magnet to raise the latch of the motor circuit relay, causing the motor to stop and the talking circuit of the 115 apparatus to open.

If the subscriber wants to kill the apparatus, he will press a push button, the action of which is to close a circuit through the magnet to release the dog and ratchet of the 120 step by step mechanism; the ratchet bar and reproducer return by the aid of a spring to 0 and at that position the ringing circuit of the apparatus is open, thus cutting it out of use. Should a call now come in, it only 125 acts on the regular telephone.

If the subscriber is away from his phone and wishes to have the apparatus set to any code number, he can call information operator at central, who, having a reset machine 130

for this purpose, presses a push button which sends a current along the positive line through a release relay which closes the circuit for the release magnet which allows the 5 spring to return the hand and reproducer apparatus to 0. While still pressing this button, she revolves the reset dial to the proper code number asked for and releases the push button. The dial now turns back 10 to its normal position and in so doing sends impulses along the negative line to operate a reset relay which in turn closes a circuit to operate the reset magnets which through the action of a ratchet bar and dog move 15 the reproducing apparatus to the desired new code number position.

If the subscriber leaves the receiver off the hook central wishing to call him is unable to do so, but with the aid of my apparatus, central can first push the button on her reset machine which sets the apparatus to 0. This opens the talking circuit of the regular telephone set which enables a ring to come in and close the apparatus end of 25 a circuit through a magnet that is not energized until the subscriber puts the receiver back on the hook, when this is done, the magnet on the apparatus is energized and its armature is restored to normal and the 30 talking circuit closed again, and the magnet circuit opened again. These magnets perform their work in an instant and no more energy is used on same.

It is obvious that the electrical connections 35 and the apparatus can be varied to conform to any changes made in the arrangement of the phonographic mechanism and that the parts may be modified in any desired manner. The cylinder type of phonograph 40 as shown is preferably employed, as the setting position of the reproducing pin can be more exactly regulated mechanically than where the disk phonographic machine is used, however the principles of my invention 45 may be embodied to the disk phonograph without departing from the spirit of the invention.

Having fully described my invention, what I now claim as new and desire to 50 secure by Letters Patent is;

1. A combined telephone and phonographic sound transmitting apparatus comprising a telephone, a telephone circuit, a phonograph and a phonographic record, a 55 telephonic transmitter and reproducer wired to the telephone circuit, said reproducer having a reproducing pin in contact with said record, a motor and means operated by the closing of the signal circuit in the 60 telephone circuit for starting the motor, said motor operating means for imparting movement to the phonograph, and to cause said reproducing pin to travel a plurality of times over a predetermined portion of

said record whereby a plurality of like 65 phonographic responses are transmitted through the telephone talking circuit from the phonographic reproducer during the operation of said motor.

2. A combined telephone and phonographic sound transmitting apparatus comprising a telephone, a telephone circuit, a phonograph and a phonographic record, a telephonic transmitter and reproducer wired 70 to the telephone circuit, said reproducer having a reproducing pin in contact with said record, a motor and means operated by the closing of the signal circuit in the telephone circuit for starting the motor, said motor operating means for imparting movement 75 to the phonograph and to cause said reproducing pin to travel a plurality of times over a predetermined portion of said record whereby a plurality of like phonographic responses are transmitted through 80 the telephone talking circuit from the phonographic reproducer during the operation of said motor, and means for stopping said motor.

3. In a combined phonograph instrument 90 and telephone, a signal circuit and a contact, a circuit closer and an electromagnet in said signal circuit, an independent circuit, an electromagnet, a latch attached to an armature on said electromagnet in said independent circuit, revolving contact means driven by motor mechanism for closing said independent circuit, a motor and a motor circuit, said motor actuating the phonograph, said motor circuit being closed by 100 the closing of the signal circuit, and means whereby said armature is held closed by said latch on the armature of the electromagnet in the independent circuit, the closing of said independent circuit by said revolving contact means energizing said magnet to release the latch and trip the motor circuit.

4. A combined telephone and phonographic sound transmitting apparatus comprising a telephone, a telephone circuit, a phonograph and a phonographic record, a telephonic transmitter wired to the telephone circuit, said transmitter having a reproducing pin in contact with said record, 110 an electric motor and a motor circuit and means operated by the closing of the signal circuit in the telephone circuit for closing the motor circuit, said motor operating means for imparting movement to the 115 phonograph, and means whereby a plurality of like phonographic responses are transmitted through the telephone talking circuit from the phonographic transmitter during 120 the closure of said motor circuit.

5. A combined telephone and phonographic sound transmitting apparatus comprising a telephone, a telephone circuit, a 125

- phonograph and phonographic record, a telephone transmitter wired to the telephone circuit, said transmitter having a reproducing pin in contact with said record, 5 an independent electric circuit and revoluble contact means in said circuit, an electric motor and a motor circuit and means operated by the closing of the signal circuit in the telephone circuit for closing the motor circuit, said motor operating means for imparting movement to the phonograph and for operating the revoluble contact means to close the independent circuit, and means whereby a plurality of like phonographic 10 responses are transmitted through the telephone talking circuit from the phonographic transmitter during the closure of said motor circuit, the closure of said independent circuit by means of the revolving 15 contact operating to trip said motor circuit.
6. In an automatic telephone and responding apparatus, a telephone and a phonograph, a telephone signal circuit, an electric motor, a motor circuit, an independent 20 circuit, an electromagnet in the signal circuit, said motor circuit being closed by the operation of the armature of said magnet on the closing of the signal circuit; a revoluble contact disk switch, operated by 25 said motor and an electromagnet in the independent circuit, the energizing of this magnet on the closing of said disk switch operating to trip the motor circuit.
7. In combined phonograph and telephone instruments, an electrically energized motor actuating the phonograph, an electromagnet energized by the telephone circuit, an independent electric circuit, an electromagnet in this circuit having an armature 30 and a latch, a revoluble insulated disk, the armature on the magnet in the telephone circuit closing the motor circuit and being held closed by the latch on the armature of the electromagnet in said independent circuit, said latch being released to trip the motor circuit by closing the independent 35 circuit thereby energizing its magnet, the wires of this circuit leading to the revoluble insulated disk operated by the motor, said 40 disk having a contact point timed to connect said wires after proper phonographic response has been transmitted through the telephone talking circuit.
8. In a combined telephone and phonographic instrument, a telephone signal circuit, an electromagnet and an armature controlled by said circuit, an electric motor and a motor circuit, said motor circuit being closed by the closing of the signal circuit energizing the magnet, an independent 45 electric circuit, a circuit closer for said independent circuit comprising a revoluble contact disk operated by the motor, and electrically operated means on the independent 50 circuit for tripping the motor circuit, 55 a threaded shaft and a cam shaft driven by said motor and controlling the movements of the phonographic instrument.
9. In the mechanism for controlling phonographs, a motor and a motor circuit, an electromagnet and an armature acting to close the motor circuit, an independent electric circuit, the time of closing of which governs the duration of closure of the motor circuit, power transmitting gears operated 60 by said motor, a threaded shaft and a cam shaft driven by said gears, said shafts controlling the movements of the phonograph, and a revolving contact disk driven by the motor, timing the closing of the independent 65 electric circuit.
10. In a phonograph, the combination with the record and sound reproducing diaphragm and holder, an indicator plate having numerical registrations thereon corresponding numerically with registrations on the record, a shaft terminating in a hand adapted to be set to any number indicated on the plate, a ratchet wheel on said shaft, a rack bar having a guide holder and spring attached thereto, said ratchet wheel meshing with said rack bar, said guide holder and spring thereby controlling the position and movement of said sound reproducing 70 diaphragm and holder.
11. In a combined telephone and phonographic instrument, the combination with means on the phonograph for automatically closing the telephone circuit, of a record indicator dial, a phonographic record, a shaft 75 and a rack bar, a ratchet wheel on the shaft engaging said rack bar, a movable hand attached to the shaft, and a guide holder on the rack bar, controlled by the movement of the hand and shaft, for moving the arm of the 80 diaphragm holder to any predetermined point, said arm being flexibly attached to said guide holder to permit of independent movements of said diaphragm holder within certain limits.
12. In a combined telephone and phonograph instrument, the combination with the record reproducing apparatus and the transmitter on the phonograph and with means for automatically closing the telephone talking circuit through said transmitter and with an electric motor operating said phonograph; of a rotary shaft actuated by the motor, a plurality of cam devices fashioned on said shaft, said record reproducing apparatus having a pin and an arm, devices on said arm acting with said cam devices to cause a plurality of movements of the reproducing pin over the same portions of the record, during the time the motor is 85 operating.
13. In a combined telephone and phonograph instrument, the combination of the

reproducing pin and telephone transmitter on the phonograph and means for automatically closing the telephone circuit through said transmitter; of means for regulating 5 the position of the reproducing pin to any predetermined position on the record and of means for causing said pin to travel a plurality of times over the same identical portion of the record during a single closing of the telephone circuit, whereby a repetition of a predetermined record is telephonically transmitted.

14. In a combined telephone and phonograph instrument, automatic means for closing 15 the telephone circuit through a transmitter on the phonograph and automatic means for resetting the phonograph instrument a plurality of times during one closure of said circuit whereby a plurality of responses of the same identical phonographic 20 response is telephonically transmitted.

15. In a combined telephone and phonograph instrument, a telephone signal circuit, said circuit having a contact, a circuit closer, 25 an electromagnet and an armature; an independent circuit, an electromagnet having an armature with a latch attached thereto, a motor and motor circuit actuating the phonograph, said motor circuit being closed by 30 the closing of the signal circuit and means whereby said armature of the electromagnet of the signal circuit is held closed by said latch; a revolving contact disk driven by said motor, a shaft, back gearing and a 35 revoluble contact drum, said disk being slidably mounted on said shaft and engaged through the back gear mechanism with the drum, said disk making a plurality of revolutions during one revolution of the drum, 40 the disk being in series with one section of the drum in the independent circuit so that when the contacts on said disk and drum section coincide, said circuit is closed energizing its magnet to release the latch and 45 trip the motor circuit.

16. A combined telephone and phonograph sound reproducing apparatus consisting of a telephone and phonograph, a transmitter on said phonograph, a motor circuit, electrically controlled apparatus in the telephone signal circuit for closing said motor circuit, a motor in said motor circuit operating means for imparting movement to the phonograph whereby a plurality of 55 like predetermined responses are phonographically transmitted through the telephone talking circuit from the transmitter on such apparatus during the closure of said motor circuit, and an independent electric circuit, a revolving contact disk driven by the motor, back gear mechanism, a revoluble contact drum and electrically controlled circuit tripping apparatus and means, said disk being slidably mounted to engage said back gearing and drive said

drum, said disk being in series with one section of the drum in said independent circuit, so that when the contacts on said disk and drum section coincide, said circuit is closed, whereby said circuit tripping apparatus operates to trip the motor circuit.

17. A combined telephone and phonograph sound reproducing apparatus, consisting of a telephone and a phonograph, a transmitter on said phonograph, a motor and a motor circuit, electrically controlled apparatus in the telephone signal circuit for closing said motor circuit, means for imparting movement to said phonograph operated by said motor and means whereby 80 a plurality of like predetermined phonographic responses are transmitted through the telephone talking circuit from said transmitter during the closure of the motor circuit; and revolving contact mechanism operating during said closure of the motor circuit for opening said motor circuit after such plurality of phonographic responses have been made, and means whereby a second closing of said signal circuit rings the 90 telephone bell only.

18. A combined telephone and phonograph sound reproducing apparatus consisting of a telephone and phonograph, a transmitter on said phonograph, a motor and a motor circuit, electrically controlled apparatus in the telephone signal circuit for closing the motor circuit, means operated by said motor for imparting movement to the phonograph and means whereby a plurality of like 100 predetermined phonographic responses are transmitted through the telephone talking circuit from said transmitter during the closure of the motor circuit; an independent electric circuit, a revolving contact disk 105 driven by the motor, back gear mechanism, a back gear wheel, a revoluble contact drum, a spring and electrically controlled circuit tripping apparatus and means, said disk being slidably mounted to engage through 110 said back gear mechanism and drive said drum, and means whereby said disk makes a plurality of revolutions during one revolution of the drum, and an electric circuit, an electromagnet and a contact section on the drum in said circuit, said circuit being closed by releasing the telephone hook lever to form a contact, thereby energizing said magnet, the armature of which disengages said back gear wheel from the contact disk, 115 whereby the spring returns the drum to its original position, when upon the revolving disk coming on contact, the independent circuit is closed, whereby said circuit tripping apparatus operates to trip the motor circuit.

19. A combined telephone and phonograph sound reproducing apparatus, consisting of a telephone and phonograph, a transmitter on said phonograph, a motor and

- a motor circuit, electrically controlled apparatus in the telephone signal circuit for closing the motor circuit, means operated by said motor for imparting movement to the phonograph, and means whereby a plurality of like predetermined phonographic responses are transmitted through the telephone talking circuit from said transmitter during the closure of the motor circuit; an 10 independent electric circuit, a revolving contact disk driven by the motor, back gear mechanism, a back gear wheel, a revoluble contact drum, a spring, and electrically controlled circuit tripping apparatus and 15 means, said disk being slidably mounted to engage through said back gear mechanism and drive said drum, and means whereby said disk makes a plurality of revolutions during one revolution of the drum, and an 20 electric circuit, an electro magnet and a contact section on the drum in said circuit, said circuit being closed by releasing the telephone hook lever to form a contact thereby energizing said magnet, the armature of 25 which disengages the back gear wheel from the contact disk, whereby the spring returns the drum to its original position, when upon the revolving disk coming on contact, the independent circuit is closed, whereby 30 said circuit tripping apparatus operates to trip the motor circuit, the energizing of said magnets consuming line energy for an instant only.
20. In a combined telephone and phonograph instrument, an indicator dial, a shaft and a rack bar driven by a gear on said shaft, said bar having attached means for controlling the position of the sound reproducing mechanism of the phonograph, a 35 hand on said shaft pointing to some number on the dial corresponding to the position of the sound reproducing mechanism to effect a suitable predetermined response; and mechanical means electrically operated for 40 returning said hand, shaft, rack bar and allied mechanism to their normal position whereby the phonograph mechanism does not operate during telephone signals.
21. In a combined telephone and phonograph instrument, an indicator dial, a shaft and a rack bar driven by a gear on said shaft, said bar having attached means for controlling the position of the sound reproducing mechanism of the phonograph, a 45 hand on said shaft pointing to some number on the dial corresponding to the position of the sound reproducing mechanism to effect a suitable predetermined response; and mechanical means electrically operated for 50 returning said hand, shaft, rack bar and allied mechanism to their normal position whereby the phonograph mechanism does not operate during telephone signals; a step by step mechanism and other means electrically operating through said step by step 55
- mechanism for setting said shaft, hand and sound reproducing mechanism to some new position to effect a desired phonographic response during a closure of the telephone talking circuit. 60
22. In a combined telephone and phonograph instrument, an indicator dial, a shaft, a dog and ratchet, a gear and ratchet wheel on said shaft, a rack bar driven by said gear, and means attached to said rack bar for 65 controlling the position of the sound reproducing mechanism of the phonograph, a hand on said shaft pointing to some number on the indicator dial corresponding to the position of the sound reproducing mechanism to effect a suitable predetermined response, a push button actuating a switch to close an electric circuit through one or more electromagnets to release a dog and ratchet from said ratchet wheel on said 70 shaft, a spring and means whereby said spring returns said shaft, hand and connected mechanism to a normal position and means whereby the phonographic mechanism does not operate during telephonic 75 signals.
23. In a combined telephone and phonograph instrument, an indicator dial, a shaft, a dog and ratchet, a gear and a ratchet wheel on said shaft, a rack bar driven by 80 said gear, and means attached to said rack bar for controlling the position of the sound reproducing mechanism of the phonograph, a hand on said shaft pointing to some number on the indicator dial corresponding to the position of the sound reproducing mechanism to effect a suitable predetermined response, a push button actuating a switch to close an electric circuit through one or more electromagnets to release a dog and ratchet from said ratchet wheel on said 85 shaft, a spring and means whereby said spring returns said shaft, hand and connected mechanism to a normal position and means whereby the phonographic mechanism does not operate during telephonic 90 signals.
24. In a combined telephone and phonograph instrument, an indicator dial, a shaft, a dog and ratchet, a gear and a ratchet wheel on said shaft, a rack bar driven by 95 said gear, and means attached to said rack bar for controlling the position of the sound reproducing mechanism of the phonograph, a hand on said shaft pointing to some number on the indicator dial corresponding to the position of the sound reproducing mechanism to effect a suitable predetermined response, a push button actuating a switch to close an electric circuit through one or more electromagnets to release a dog and ratchet from said ratchet wheel on said 100 shaft, a spring and means whereby said spring returns said shaft, hand and connected mechanism to a normal position and means whereby the phonographic mechanism does not operate during telephonic 105 signals.
25. In a combined telephone and phonograph instrument, an indicator dial, a shaft, a dog and ratchet, a gear and a ratchet wheel on said shaft, a rack bar driven by 110 said gear, and means attached to said rack bar for controlling the position of the sound reproducing mechanism of the phonograph, a hand on said shaft pointing to some number on the indicator dial corresponding to the position of the sound reproducing mechanism to effect a suitable predetermined response, a push button actuating a switch to close an electric circuit through one or more electromagnets to release a dog and ratchet from said ratchet wheel on said 115 shaft, a spring and means whereby said spring returns said shaft, hand and connected mechanism to a normal position and means whereby the phonographic mechanism does not operate during telephonic 120 signals.
26. In a combined telephone and phonograph instrument, an indicator dial, a shaft, a dog and ratchet, a gear and a ratchet wheel on said shaft, a rack bar driven by 125 said gear, and means attached to said rack bar for controlling the position of the sound reproducing mechanism of the phonograph, a hand on said shaft pointing to some number on the indicator dial corresponding to the position of the sound reproducing mechanism to effect a suitable predetermined response, a push button actuating a switch to close an electric circuit through one or more electromagnets to release a dog and ratchet from said ratchet wheel on said 130 shaft, a spring and means whereby said spring returns said shaft, hand and connected mechanism to a normal position and means whereby the phonographic mechanism does not operate during telephonic 135 signals.

lay magnet, an electric circuit and an electromagnet, the armature of said relay magnet closing said latter circuit through said electromagnet to release a dog and ratchet bar from the ratchet wheel whereby said spring returns said shaft, hand and connected mechanism to a normal position; a numbered indicator dial on said reset machine corresponding to the indicator dial on 5 the combined telephone and phonograph instrument, a shaft and clock mechanism in said reset machine, said reset dial being connected to said shaft, this shaft being revolvable by said clock mechanism when the indicator dial is set to a desired number, ratchet wheels on said dial shaft for controlling the 10 position of the reset dial, pawl bars and cam means for driving said bars operated by said push button, said pawl bars controlling 15 said ratchet wheels; a contact gear on the dial shaft, a contact point, an electric circuit, a relay magnet, another electric circuit, a step by step mechanism, electromagnets in 20 said mechanism, the teeth of such contact gear, during rotation of the reset dial back to its normal position, touching said contact point in sequence thereby sending electric 25 impulses over said circuit to operate said relay magnet, which in turn closes the second 30 circuit to energize the magnets in the step by step mechanism, whose armature and attached ratchet bar move the first mentioned ratchet wheel, its attached shaft, hand and 35 sound reproducing mechanism to the desired position thereby setting the combined telephone and phonographic apparatus to a new position adapted to transmit a desired phonographic response through the telephone talking circuit.

40 25. In a combined telephone and phonograph instrument, a closed transmitter circuit, a reset machine, mechanical means on

said reset machine electrically operating to disconnect the phonograph and open the transmitter telephone circuit.

45

26. In a combined telephone and phonograph instrument, a closed transmitter circuit, a reset machine, mechanical means on said reset machine electrically operating to disconnect the phonographic apparatus and open the transmitter telephone circuit to enable a ring to be made.

27. In a combined telephone and phonograph instrument, a closed transmitter circuit, a reset machine, mechanical means on 55 said reset machine electrically operating to disconnect the phonographic apparatus and open the transmitter telephone circuit to enable a ring to be made; an electromagnet and an electric circuit, a hook operated by 60 the armature of said magnet, the closing of said circuit, by hanging up the telephone receiver, energizing said magnet to disconnect said hook thereby enabling a contact to be made to be made to close the transmitter circuit. 65

28. In a combined telephone and phonographic instrument, a closed transmitter circuit, a reset machine, mechanical means on said reset machine electrically operating to disconnect the phonographic apparatus and 70 open the transmitter circuit to enable a ring to be made; an electromagnet and an electric circuit, a hook operated by the armature of said magnet, the closing of said circuit, by hanging up the telephone receiver, 75 energizing said magnet to disconnect said hook thereby enabling a contact to be made to close the transmitter circuit, the energizing of said magnet consuming line energy for an instant only.

EDWARD J. CRESSEY.
